UNITED STATES PATENT OFFICE.

JOHN M. BOUCK, OF GOVERNEUR, NEW YORK.

CAR-COUPING.

SPECIFICATION forming part of Letters Patent No. 398,123, dated February 19, 1889.

Application filed June 5, 1888. Serial No. 276,119. (No model.)

To all whom it may concern.

Be it known that I, JOHN M. BOUCK, a citizen of the United States, residing at Gouverneur, in the county of St. Lawrence, State of New York, have invented a certain new and useful Improvement in Car-Couplers, of which the following is so full, clear, and exact a description as will enable others skilled in the art to which my invention appertains to make and use the same, reference being had to the accompanying drawings.

The object of my invention is to provide a car-coupler which shall dispense with the ordinary coupling-link now in use on freight-cars, and enable the brakeman to couple his cars together without getting between the cars, and thus avoid the risk of danger to life and limb.

Another object of my invention is to provide a coupler which shall be easily used with the coupling-links of the ordinary coupler when necessary, thus avoiding the necessity of suddenly abandoning many old cars and undergoing great expense thereby.

Another object of my invention is to provide a coupler that shall be operative between cars of different heights of platform as well as between cars having their platforms on the same level.

Another object of my invention is to provide a coupler which may be operated from the platform of the car, when the car has a platform, which is not unfrequently the case with freight-cars.

These objects I accomplish by the device which is hereinafter described, and which is illustrated in the accompanying drawings, in which—

Figure 1 is a longitudinal section of one end of a car, showing my coupler in section as mounted on the car. Fig. 2 is a front view of a car with the front transverse beam removed, showing my coupler in end view and with the two devices whereby it is operated from the platform and coupled to the old form of car, respectively. Fig. 3 is a back view of the front floor-beam of a car, showing the attachment and working of the lifting-levers.

Fig. 4 is a top view of the front floor-beam of a car with a part of the floor removed, showing the arrangement of bent levers, whereby the coupler may be lifted from a point as far

from the end of the car as is wished. Fig. 5 is a top view of the middle section of the coupler-bar, showing its construction in two pieces. Fig. 6 is a top view of one of the outer sections or jaws of the coupler-bar, showing in dotted lines the arrangement of the guard-buffer, whereby the car is prepared to be coupled to a car of the old form. Fig. 7 is a side view of the guard-buffer itself. Fig. 8 is a side view of the bridle D. Fig. 9 is an end front view of bridle D, showing the oblong aperture d. Fig. 10 is a top view of the bridle D.

Throughout the accompanying drawings and in the following specification the same reference-letters designate corresponding parts in the various views.

The coupler-bar A is formed in three general sections—one central section, a, and two outer sections or jaws, b b—which are built together, as follows: The central section, a, may be made in one piece, as shown in Fig. 1, or it may be made in two pieces, as shown in Fig. 5. This section a is composed of a body, A', ahead, a'', and a shank, a'. The head, as shown in Fig. 5, is formed to supply a jaw for the reception of the projections e, and also a part of the buffer f. The head a'' and the body A' are both perforated for the reception of bolts designed to fasten them to the outer sections, b b. The shank a' is a smooth cylinder for a part of its length, and is screw-threaded toward the end. The outer sections or jaws, b b, are made alike and are composed of one piece cut as shown in Fig. 6. The head b' is made to fit over the head of the middle section, so that the three forward holes m of the outer sections will come exactly over the three corresponding holes in the middle section. The point e is designed to project beyond the buffers f, and is perforated at o by an oblong aperture. The aperture o in the upper jaw b is cut so as to fall directly above that in the lower jaw b, and the centers of both holes fall approximately in the plane of contact of the buffers. This aperture is intended for the reception of the coupling-pin p. These three sections of the coupler-bar A having been placed in the relative positions shown in Fig. 1 are bolted together through the holes shown in Figs. 5 and 6, and the bar is then hung in place, as follows:

Under the front sill-beam of the car is bolted a coupler-saddle, S. (Shown in end view in Fig. 3.) The body of the coupler-bar rests in this saddle, with the head extending forward 5 beyond the under edge of the car, and with the shank a' supported by a bridle, D, and a toggle-joint, J, as shown in Fig. 1. Just back of the sill E and under the body of the coupler-bar A the two levers shown in section at l in 10 Fig. 1 are placed, and serve to raise the coupler-bar through the space shown at u in Fig. 3. Just back of the body of the coupler-bar is placed a disk, W, which surrounds the shank of the coupler-bar, and to which is attached a spiral spring, v, which extends from this disk to the bridle at the point d, where the shank of the coupler-bar passes through 15 said bridle. Beyond the point d there is another spiral spring, v', which extends from the bridle to the toggle-joint J.

The bridle D is fully exhibited in Figs. 8, 9, and 10. As seen in Fig. 10, it is composed of two shanks, D' D', which are joined by a guide-piece, d', in which is cut an aperture, d, 20 made oblong in the vertical direction to allow of an up-and-down play of the coupler-bar A. The two shanks are designed to be attached by means of bolts through the holes shown in Fig. 8 to the two middle longitudinal beams of 25 the car-body.

The toggle-joint, as shown in Fig. 1, is composed of two rigid pieces, g and g', fixed, respectively, to the supporting-bar c and to the nut r. Between these two rigid pieces is pivoted another piece, i, which is free to turn 30 about the two pivots shown at x and t in Fig. 1. The bearing of pivot t in the upper rigid piece is made oblong in the direction of the car-axis, and is designed to permit a backward and forward play of the toggle-joint. The lower rigid piece of this joint is attached 35 to the nut r, into which is screwed the end of the shank a' .

In Fig. 3 is shown the arrangement of side 40 levers, L and L', by means of which the coupler-bar A is raised through the distance E. The two pivotal supports s are fastened to the back surface of the forward sill, and by means of a downward pressure on the handles h the 45 levers may be operated. These levers are so balanced that the weight of the handles keeps the working ends always in contact with the coupler-bar.

In Fig. 4 is shown a bent-handled lever, 50 which acts in practically the same manner as the others; but by reason of the backward turn in the handle the operator is not obliged to be near the end of the car when the two cars come together.

In Fig. 2 the front of the car is shown with 55 the front sill removed in order to expose the action of the treadle P in the raising of the coupler-bar from the platform of the car.

The strap I supports a pivot, I', about which 60 the lever L'' is turned by means of the downward thrust of the post F, operated from the platform by pressure of the foot on the

treadle P. At G is shown a flat hook fixed to the top of the truck-beam H, and upon which the guard-buffer B may be hung when not in use. In Fig. 2 this guard-buffer is shown hung upon the hook G. The construction of this guard-buffer is shown in detail in Fig. 7, where the buffer is shown from the top when in action. B'' B'' are two solid metallic buffers, forming one piece with the two lips B' B', which connect them, the whole being so proportioned as to fit snugly over the jaws of the coupler-bar, as shown in dotted lines in Fig. 6. The hole o' is made the same in size 70 as the hole o in Fig. 6, and may or may not be made oblong for the same reason—namely, in order to allow of greater lateral bending between the cars when turning a curve. It will be readily seen that when in position this 75 guard-buffer will present a surface to the buffer of the contiguous car similar to that presented by the buffers of the present form of car.

My improved car-coupler will then be operated as follows: When two cars furnished with my coupler are brought together for coupling, if the coupler-bars are on the same level, the brakeman will depress the handle of the lever L, L', or L'', according to the position 80 he finds it necessary to take, and depending upon whether the car has a platform or not, and thus slightly raise the coupler-bar, allowing the jaw-points e e of one bar to alternate with the corresponding jaw-points of the other. Once in this position, the pin p may be inserted without going between the cars either from the platform or from the side of the car. If, however, the cars are not built 85 equally high, the jaws will naturally assume the proper position as they come together without the operation of the lever, the coupler on the lower car taking the position shown in dotted lines as that of the bar. As the cars 90 come together, the buffers f on the bars of one car will strike the corresponding buffers on the bar of the other car, and the shock will be taken up with the easiest motion possible by the spiral springs v and v' and the toggle-joint J. When it is required to couple one 95 of my coupler-bars with the old form of coupler now in use, a buffer corresponding to the old form of buffer must be provided, or the jaw-points of my coupler will be jammed and seriously damaged by the shock of the 100 meeting. For this purpose I have contrived a guard-buffer which is adjustable to the head of my coupler-bar, and which, when not in use, can be hung up out of the way upon the hook G. To operate this guard, it is simply fitted over the points of my coupler-bar 105 in such a way as to bring the oblong hole o' over the corresponding hole o, and then by inserting the old coupling-pin into the jaw k the cars may be coupled by dropping the pin 110 p through the three superposed holes in my coupler-bar.

Hitherto brakemen have been obliged to risk serious injuries, and often a horrible

death, by entering the space between the cars in order to hold the coupling-link in place while the moving car was approaching. All necessity for this risk is obviated by the use 5 of my device. Another objection to the present system of car-coupling is that when cars of unequal heights are coupled together the pull on the pin is not a straight one, but includes a twisting effect which endangers not 10 only the pin, but the link as well. By the use of my device the pull upon the pin is invariably straight, and all twisting and wrenching are avoided.

I do not wish to be understood as limiting 15 myself to the exact construction described, as it is obvious that minor details of construction may be altered or varied without departing from the spirit of my invention and without interfering materially with the usefulness 20 of the same.

Having now described the objects, uses, and advantages of my invention, and having set forth a preferred method of construction, what I believe to be new, and desire to secure 25 by Letters Patent of the United States, and what I therefore claim, is—

1. In a car-coupler, a recessed coupler-bar provided with a nut, *r*, having a rigid piece, *g*, secured thereto, in combination with a link, 30 *i*, and a second rigid piece, *g'*, secured to a supporting-bar, *c*, said rigid pieces *g'* having an oblong perforation, the longer axis of which extends in the direction of the track, said link *i* being pivoted to said rigid pieces 35 *g* and *g'* by one pivot-pin extending through said oblong perforation, substantially as and for the purposes specified.

2. In a car-coupler, a recessed coupler-bar provided with a nut, *r*, having a rigid piece, 40 *g*, secured thereto, in combination with a link, *i*, and a second rigid piece, *g'*, secured to a supporting-bar, *c*, said rigid piece *g'* having an oblong perforation, the longer axis of which extends in the direction of the track, 45 said link *i* being pivoted to said rigid pieces *g* and *g'* by one pivot-pin extending through said oblong perforation, and a pair of levers, *L* and *L'*, the inner ends of which bear against the under side of the coupler-bar and the 50 outer ends provided with handles, substantially as and for the purposes specified.

3. In a car-coupler, a recessed coupling-bar provided with a nut, *r*, having a rigid piece, *g*, secured thereto, in combination with a link,

i, and a second rigid piece, *g'*, secured to a 55 supporting-bar, *c*, said rigid piece *g'* having an oblong perforation, the longer axis of which extends in the direction of the track, said link *i* being pivoted to said rigid pieces *g* and *g'* by one pivot-pin extending through 60 said oblong perforation, and a pair of levers, *L* and *L'*, the inner ends of which bear against the under side of the coupling-bar and the outer ends provided with handles, one of said levers having an auxiliary foot-post extending 65 up through the platform, substantially as described.

4. In a car-coupler, the combination of a recessed coupler-bar provided with a nut, *r*, having a rigid piece, *g*, secured thereto, with 70 a link, *i*, and a second rigid piece, *g'*, secured to a supporting-bar, *c*, said rigid piece *g'* having an oblong perforation, the longer axis of which extends in the direction of the track, said link *i* being pivoted to said rigid pieces 75 *g* and *g'* by one pivot-pin extending through said oblong perforation, and a buffer-guard having perforated lips, which are adapted to embrace the perforated jaws of the coupling, the perforations in the buffer registering with 80 those of the coupling, substantially as described.

5. In a car-coupler, a pair of coupler-bars supported at their rear ends by a toggle-joint and supported near their jaws by saddles, and 85 free to move vertically and horizontally within predetermined limits, in combination with bridle *D*, and coiled springs encircling the coupler-bars and abutting against the bridle from opposite sides, substantially as and for 90 the purposes specified.

6. In a car-coupler, a pair of coupler-bars supported at their rear ends by toggle-joints and supported near their jaws by saddles, and free to move vertically and horizontally within 95 predetermined limits, in combination with bridle *D*, and a disk, *W*, loosely mounted on the coupler-bar, and a coiled spring between said disk and bridle, and a second coiled spring between said bridle and the toggle-joint, all constructed and combined to operate substantially as described.

In testimony whereof I affix my signature in the presence of two witnesses.

JOHN M. BOUCK.
